CARVING KNIFE OR SIMILAR ARTICLE

Haim J. Shwisha, 2 Beekman Place, New York, N.Y.

Filed Oct. 22, 1963, Ser. No. 77,086

Term of patent 14 years

(Cl. D22—3)

FIG. 1

FIG. 2

FIGURE 1 is a perspective view of a carving knife or similar article showing the top and one side of my new design.

FIGURE 2 is another perspective view of a carving knife or similar article showing the bottom and other side of my new design.

The essential features of the design reside in the full line portions of the drawings.

I claim:

The ornamental design for a carving knife or similar article, substantially as shown and described.
